UNITED STATES PATENT OFFICE.

JAMES R. PAINE, OF BALTIMORE, MARYLAND.

DESIGN FOR A STRAW HAT.

SPECIFICATION forming part of Design No. 34,613, dated June 4, 1901.

Application filed April 16, 1901. Serial No. 56,169. Term of patent 3½ years.

To all whom it may concern:

Be it known that I, JAMES R. PAINE, a citizen of the United States, residing at Baltimore, State of Maryland, have invented and produced a new and original Design for a Straw Hat, of which the following is a specification.

Reference is to be had to the accompanying drawings, in which—

Figure 1 is a top plan view of the straw hat embodying the design. Fig. 2 is a front view of the same. Fig. 3 is a top plan view of the crown of the hat sectioned on the line 3 3 of Fig. 2.

The design consists in the shape and configuration of the straw hat shown in the accompanying drawings, in which the crown *a* of the hat appears with a substantially flat upper surface *b* and a substantially vertical side surface *c*, and a plurality of indentations *d* appear where the said side surface merges

into the said upper surface. These indentations are a permanent feature of the configuration of the crown of the hat and are five in number, as shown particularly in Fig. 1 of 25 the drawings, two being located one on each side of the front of the crown, another directly at the rear of the crown, and the remaining two at corresponding opposite points on the sides of the crown near the rear thereof, one on each side of the said rear indentation. 30

I claim—

The design for a straw hat as herein shown and described. 35

In testimony whereof I affix my signature in the presence of two witnesses.

JAMES R. PAINE.

Witnesses:

F. S. STITT,
WALTER E. SMITH.
